UNITED STATES PATENT OFFICE.

ELMER E. SCHELLENGER, OF RIVERSIDE, CALIFORNIA.

DUMPING-WAGON.

1,029,895.

Specification of Letters Patent. Patented June 18, 1912.

Application filed December 10, 1910. Serial No. 596,725.

To all whom it may concern:

Be it known that I, ELMER E. SCHELLENGER, citizen of the United States, residing at Riverside, in the county of Riverside and State of California, have invented certain new and useful Improvements in Dumping Wagons, of which the following is a specification.

My invention relates to dumping wagons and particularly to that class of dumping wagons forming the subject of my pending application for Patent, Serial No. 592,399, filed on the 14th day of November, 1910, the object of the invention being to provide a dumping wagon with means whereby the load as it is dumped may be distributed to a uniform depth upon the ground as the wagon moves forward, this depth being capable of regulation, the regulating means also providing means for giving the crown of the material so distributed any desired inclination.

Another object of the invention is to provide a device of this character adapted to cover any area of any length and having any varying cross section across its width.

A further object is to provide a device of this character which is capable of unloading and discharging its load under the control and will of the operator.

A further object is to provide a dumping wagon having a discharge regulating device thereon, which not only regulates the rate of discharge of the load from the wagon, but also regulates the depth of the distributed material and does this automatically as the wagon moves along the roadway or ground upon which the material is being discharged.

In my prior application I have shown an attachment which is not permanently fastened or attached to the wagon body but which is engaged by each wagon in turn as the wagon comes to unload, which attachment acts as above described. In the present application I provide, generally speaking, a dumping wagon having a discharge opening extending transversely across the wagon, this discharge opening being provided with opposed gates, one of the gates forming a continuation of the wagon hopper while the other gate provides a depth-regulating blade which carries forward the surplus material as it is discharged from the hopper and distributes it.

My invention is shown in the accompanying drawings wherein:

Figure 1 is a side elevation of my improved wagon, the gates being shown in their dumping position. Fig. 2 is a rear view of the lower end of the hopper, the gate and blade being shown in elevation. Fig. 3 is a horizontal section of the lower end of the hopper at its junction with the gates.

Corresponding and like parts are referred to in the following description and indicated in all the views of the accompanying drawings by the same reference characters.

Referring to these figures, 2 designates a wagon of any desired character and having thereon the wagon body 3. This wagon body has the shape of a hopper, the lower end of the hopper being formed with a discharge opening 4 extending entirely across the hopper. Hingedly mounted upon the front wall of the lowest portion of the hopper, forward of the opening 4, is the gate 5 or forward door. This gate 5 has the side wings 6 which have the form of segments of circles, the gate 5 being of such width that these side wings, when the gate is closed, extend up on each side on the outside of the hopper. The free end of the door or gate 5 is attached to limiting chains 7 which extend up on either side of the hopper and at their upper ends are attached to the body 8 of the hopper as at 8. These limiting chains or connections 7 simply hold the door or gate 5, when lowered, in alignment with the front wall of the hopper and therefore at a proper inclination to discharge the material 9 from the hopper. It will be seen that this gate 5 causes the material from the hopper to be discharged in a rearward direction.

Hingedly mounted upon the rear wall of the hopper adjacent to the opening 4 is the rear gate or door 9. This door is slightly longer than the width of the hopper opening and is provided upon its sides with the wings 10, which when the door is closed extend up on the outside of the lower end of the hopper, as shown in dotted lines in Fig. 1. The forward end of the door 9 and the forward end of the door or gate 5 are connected by flexible connections 11 so that when the gate 5 is in the position shown in full lines in Fig. 1, the gate or door 9 will be practically at right angles to the roadbed. The connection 11 is attached to a flexible cord or chain

12 which passes over a pulley 13 and preferably extends to a windlass or like winding device 14 actuated in any suitable manner. As illustrated, the windlass 14 is actuated by means of a lever 15 having a bolt 16 engaging with a toothed gear 17 mounted upon the windlass. A pawl 18 is provided which will prevent the unwinding of the windlass and hold it in any adjusted position, this pawl having a lever projecting up in front of the dashboard in convenient position to the driver. This form of windlass and operating lever therefor being old requires no further description. It will be understood that there is a connection 12 on each side of the hopper, this connection being attached to a connection 11 located one on each side of the gate 9 just inside of the wings 10.

The wings 10 are preferably formed as terminations of a blade 20 which is attached to the back of the door 9 and extends transversely across the same, as illustrated in Fig. 2. This blade 20 is so attached to the door 9 that it may be raised or lowered at either or both ends. For the purpose of providing for this attachment, the blade is shown as formed with a plurality of openings 23, these openings increasing in size as they are located nearer to the upper edge of the blade. Bolts 22 pass through these openings and adjustably attach the blade to the door 9. The wings 10 extend outwardly and laterally at a slight inclination as shown in Fig. 3. The blade may be adjusted so as to extend to any desired degree below the lower edge of the door 9 and it will be obvious that the blade may be set at any desired angle, the elongated slots permitting this angular adjustment of the blade.

The operation of my invention is as follows. When the wagon has reached the place at which the load is to be dumped, as for instance a roadway which is to be covered with broken stone, gravel or sand, the driver releases the connection 12, by operating the lever 15, and permits the door 5 to open into alignment with the front wall of the hopper, while the door 9 drops down into a position at right angles with the road bed. Under these circumstances the load will commence to pass downward from the hopper and will be directed rearward by the door 5, the door 5 with its wings 6 acting as an extension of the hopper. The scraper or blade 20 as the wagon moves forward pushes the material ahead of it and levels the material engaged by it as illustrated in Fig. 1. The excess of the material will therefore be carried forward and properly distributed until the wagon is empty. It will be seen that the forward door 5 primarily lengthens or increases the capacity of the wagon without sacrificing any of the advantages of the hopper-shaped body. It also acts, however, to reduce the draft power

which is required to crowd ahead and cut off the road material to a uniform level by reducing the cross section between the bottom of the door 9 and the bottom edge of the door 5 when open. This prevents the material released from pouring ahead farther than a very limited distance and thus the material is not scattered but is held well within the bounds of the wings 10.

It is to be noted that the wings 6 and 10 extend up on the outside of the hopper when the doors are closed. This prevents the doors from becoming jammed by material getting wedged in between the wings and the side of the hopper, and furthermore it will of course be obvious that the wings 11 being flared and being attached to the blade, which is wider than the hopper, must be outside.

While I have shown what I believe to be a very effective form of my device, I do not wish to be limited to all these details as it is obvious that many changes might be made therein, the principal feature of my invention being the provision of a distributing blade located immediately in rear of the hopper opening so that all material passing out of the hopper opening will be pushed along by the blade and the material leveled by the lower edge of the blade.

It will be seen that by the use of my device the material may be distributed to a uniform depth for any desired distance and that this material will also have a uniform width. The material may be distributed to a greater width by repeating the operation, that is, driving the wagon parallel to its first path of travel. Thus the wagon is capable of covering any area of any width or any length to a uniform depth. Furthermore, it will be obvious that a road of any cross section may be fully covered across its width and that it matters not whether the road be stepped, concave or convex, and that the distributed material may be given any desired conformation, either stepped, concave or convex by raising or lowering both ends of the adjustable blade. The edge of the adjustable blade may be given any particular form desired to produce any particular result.

What I claim is:

1. A dumping wagon having a discharge opening extending transversely across it, a distributing blade supported upon the bottom of the wagon rearward of the discharge opening and extending entirely across it, said blade being independently adjustable vertically at each end thereof.

2. A dumping wagon having a discharge opening extending transversely across it, a gate pivoted to the bottom of the wagon at the rear end of said discharge opening, said gate being adapted to swing into a position to partially close the discharge opening, or

into a vertical position, and a distributor mounted upon said gate and projecting below the free edge thereof and vertically adjustable with relation thereto.

5. A dumping wagon having a discharge opening extending transversely across it, a gate pivoted to the bottom of the wagon at the rear end of said discharge opening, said gate being adapted to swing into a horizontal position to partially close the discharge opening, or into a vertical position, and a distributing blade adjustably mounted upon the free edge of the gate, said blade having forwardly extending wings.

4. A dumping wagon having a hopper-shaped body, and a discharge opening in the hopper-shaped body extending transversely across the wagon and having a rearwardly and downwardly extending front wall, a gate pivoted to the bottom of the hopper-shaped body forward of the discharge opening, means for limiting the opening movement of said gate to a position in alignment with the forward wall of the hopper, a gate pivoted to the bottom at the rear end of the discharge opening, a flexible connection between the free ends of both of said gates, an actuating means, and a flexible connection extending from said first named flexible connection to said actuating mechanism whereby the gates may be raised or lowered and a distributor blade

mounted upon the lower edge of the rear gate for independent vertical adjustment. 35

5. A dumping wagon having a hopper-shaped body formed with a discharge opening at its lower end extending transversely to the wagon, a gate hingedly mounted upon the bottom of the body forward of the discharge opening, said gate being provided with lateral upwardly projecting wings, means for limiting the opening movement of the gate, a gate pivoted to the body rearward of the discharge opening and adapted to swing into a vertical position, a distributing blade adjustably mounted upon said gate and having laterally and forwardly projecting inclined wings, oppositely disposed flexible connections between the free ends of both gates, pulleys mounted upon the hopper-shaped body on opposite sides thereof and above the discharge opening, flexible connections on opposite sides of the body extending down to the flexible connections connecting the gates, said connections passing over the pulleys, a windlass over which the flexible connections pass, and means for actuating the windlass.

In testimony whereof, I affix my signature in presence of two witnesses.
